US00D927482S

(12) **United States Design Patent** (10) **Patent No.:** **US D927,482 S**
(45) **Date of Patent:** **** Aug. 10, 2021**

(54) **ELECTRONIC COMPUTER**

(71) Applicant: **Dynabook Inc.**, Tokyo (JP)

(72) Inventor: **Ryo Suzuki**, Tokyo (JP)

(73) Assignee: **Dynabook Inc.**, Tokyo (JP)

(**) Term: **15 Years**

(21) Appl. No.: **29/690,496**

(22) Filed: **May 8, 2019**

(51) LOC (13) Cl. **14-02**

(52) U.S. Cl.

USPC **D14/315**

(58) **Field of Classification Search**

USPC D14/150, 168, 203.4, 203.6, 247,

CLAIM

The ornamental design for an electronic computer, as shown and described.

DESCRIPTION

FIG. 1 is a perspective view of an electronic computer showing my new design,

FIG. 2 is a front elevational view thereof,

FIG. 3 is a rear elevational view thereof,

FIG. 4 is a left side elevational view thereof,

FIG. 5 is a right side elevational view thereof,

FIG. 6 is a top plan view thereof,

FIG. 7 is a bottom plan view thereof,

FIG. 8 is a front elevational view showing an article in a closed position thereof,

FIG. 9 is a top plan view showing the article in the closed position thereof,

FIG. 10 is a rear elevational view showing the article in the closed position thereof; and,

FIG. 11 is a right side elevational view showing the article in the closed position thereof.

The broken lines illustrate portions of the electronic computer that form no part of the claimed design.

1 Claim, 10 Drawing Sheets
